UNITED STATES PATENT OFFICE.

ED ELLIS, OF GUTHRIE, OKLAHOMA, ASSIGNOR OF ONE-FOURTH TO CECIL FRANCIS HOPKINS, ONE-FOURTH TO ALPHEUS AMON LEER, AND ONE-FOURTH TO HERMAN GERLACH, ALL OF GUTHRIE, OKLAHOMA.

REFRIGERATOR WEIGHING DEVICE.

1,111,447.

Specification of Letters Patent. Patented Sept. 22, 1914.

Application filed December 13, 1913. Serial No. 806,515.

To all whom it may concern:

Be it known that I, Ed Ellis, a citizen of the United States, residing at Guthrie, in the county of Logan and State of Oklahoma, have invented certain new and useful Improvements in Refrigerator Weighing Devices; and I do hereby declare the following to be a full, clear, and exact description of the invention, such as will enable others skilled in the art to which it appertains to make and use the same.

My invention relates to new and useful improvements in weighing devices for refrigerators whereby the amount of ice placed within the refrigerator may be determined, by numbers of pounds, at all times.

An important object of my invention is to provide a cage or receptacle for containing ice that is mounted within a refrigerator and suspended by means of a suitable spring, said cage or receptacle being operatively connected with a pivoted scale needle whereby the amount of ice within the cage, in numbers of pounds may be readily determined from time to time without opening the lid or doors of the refrigerator.

Another important object of my invention is to provide a device of the character described which is extremely simple as to construction and number of parts, may be cheaply manufactured and which is capable of being installed within refrigerators without necessitating much labor or time for installing the device.

The above and additional objects are accomplished by such means as are illustrated in the accompanying drawings, described in the following specification and then more particularly pointed out in the claims which are appended hereto and form a part of this application.

With reference to the drawings, wherein I have illustrated the preferred embodiment of my invention as it is reduced to practice, and throughout the several views of which similar reference numerals designate corresponding parts, the figure represents a vertical sectional view through a refrigerator illustrating my weighing device in operative position therein.

Referring to the drawings forming a part of this specification, the numeral 1 design-

nates as an entirety a refrigerator provided with a vertical partition wall 2 which divides the refrigerator into two compartments designated A and B. The compartment A may be divided into any suitable number of subcompartments by means of transverse shelves or racks 3.

The compartment A is preferably not provided with the shelves or racks 3 so as to facilitate the sliding of a rectangular ice cage or receptacle designated 4 as an entirety. This receptacle or cage 4 is provided with an open front to facilitate the placing of the ice therein. A drain pipe 5 is connected with the bottom wall of the receptacle 4 and is adapted to extend through the bottom wall of the refrigerator 1. A helical spring 6 is adapted to support the cage or receptacle 4 and is connected at its terminals to the top wall 7 of the refrigerator and top wall 8 of the receptacle 4. A rod 9 is secured as at 10 to the top wall 8 of the receptacle 4 and extends upwardly through the helical spring 6 and through an opening 10 formed in the top wall 7 of the refrigerator.

Formed upon the top wall 7 of the refrigerator 1 is a rectangular compartment 12 adapted to contain the scale needle and graduated scale plate. This compartment 12 is provided with a glass wall 13 at the front thereof to facilitate the ready reading of the scale. The glass front 13 may if so desired only extend for a distance sufficient to permit the reading of the scale which is located at one end of the receptacle and in this connection it is not thought necessary to illustrate the above described arrangement.

The upper end of the rod 9 is extended into the compartment 12 and provided with an eye 14 adapted to receive the hook end 15 of a connecting rod 16 which is pivoted as at 17 to a scale or indicating needle 18. This indicating or scale needle 18 is pivoted as at 19 to the rear wall of the compartment 12 and is provided at its free end with a reduced point which is adapted to register with the graduations on the scale plate 21 that is preferably secured to the rear wall of the compartment 12.

Secured transversely of the compartment A adjacent the lower portion thereof is a

bar 21' provided with a plurality of bearings 22. Secured adjacent each corner of the receptacle 4 upon the bottom wall thereof are guide rods 23 that are slidably mounted 5 within the bearings 22. These guide rods 23 and coöperating parts serve to provide for the proper sliding of the cage or receptacle 4 within the compartment A. An opening 24 is formed adjacent one side of the bar 21' 10 to provide for the sliding of the drain pipe 5 therethrough. It will thus be seen that when a block of ice is placed in the cage or receptacle 4, the pull communicated to the needle 18 through the medium of the rods 9 15 and 16 causes the point of the needle 18 to register with the graduations on the scale plate 21. Thus it will be seen that the amount of ice within the cage 4 may be readily determined, by numbers of pounds, 20 at all times without necessitating opening of the doors of the refrigerator.

It is desirous of emphasizing the fact that the device hereinbefore described and illustrated in the accompanying drawings is extremely simple as to construction and number of parts and is capable of being readily attached to standard refrigerators without necessitating much time or labor.

In reduction to practice, I have found that 30 the form of my invention, illustrated in the drawings and referred to in the above description, as the preferred embodiment, is the most efficient and practical; yet realizing that the conditions concurrent with the 35 adoption of my device will necessarily vary, I desire to emphasize the fact that various minor changes in details of construction, proportion and arrangement of parts may be resorted to, when required, without sacrificing any of the advantages of my invention, as defined in the appended claims.

What is claimed is:—

1. A refrigerator weighing device comprising an ice cage adapted to be mounted within a refrigerator, a helical spring secured at its terminals to the upper end of the ice cage and to the upper wall of the refrigerator and yieldingly supporting the ice cage, a rod extending upwardly through the spring and secured at one terminal to the ice cage, the upper wall of the refrigerator having an opening therein, a compartment formed on the upper wall of the refrigerator, said rod extending into the compartment, a scale needle pivoted in the compartment, a scale plate mounted within the compartment, and a connecting rod for the first rod and scale needle, said compartment having a transparent front wall.

2. A refrigerator weighing device comprising an ice cage slidably mounted within a refrigerator, a spring operatively connected with the ice cage and the refrigerator and yieldingly supporting said ice cage, a rod secured to said cage, a compartment formed upon the upper portion of the refrigerator, said rod extending into said compartment, a scale plate mounted within said compartment, a scale needle mounted within said compartment and operatively connected with said rod at the upper end thereof, said compartment having a transparent front wall and guide bars at the lower end of said ice cage, an apertured bar mounted within the refrigerator and operating with said guide bars.

In testimony whereof I affix my signature in presence of two witnesses.

ED ELLIS.
